C. C. REITENBAUGH.
BEAM COMPASS.
APPLICATION FILED JUNE 4, 1920.

1,404,794.

Patented Jan. 31, 1922.

UNITED STATES PATENT OFFICE.

CHARLES C. REITENBAUGH, OF ROCK ISLAND, ILLINOIS.

BEAM COMPASS.

1,404,794.

Specification of Letters Patent. Patented Jan. 31, 1922.

Application filed June 4, 1920. Serial No. 386,426.

To all whom it may concern:

Be it known that I, CHARLES C. REITENBAUGH, a citizen of the United States, residing at Rock Island, in the county of Rock Island and State of Illinois, have invented certain new and useful Improvements in Beam Compasses, of which the following is a specification.

This invention relates to drafting instruments and the primary object of the invention is to provide an improved compass in which the marking leg thereof can be quickly and accurately set and maintained in its set position, thereby eliminating the inconveniences associated with the compasses now on the market.

Another object of the invention is to provide an improved drawing instrument in which the lead can be quickly removed from the marking leg, when it is desired to insert a new piece therein and thus eliminate the difficulties heretofore experienced in removing small pieces of lead from the marking leg.

Another object of the invention is to provide an improved beam compass embodying a graduated beam and a sliding marking post or leg mounted on the beam, the post or leg having an improved means for engaging the beam so as to prevent accidental movement thereon.

A still further object of the invention is to provide an improved compass of the above character which is durable and efficient in use, one that is simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawings, forming a part of this specification, in which drawings:

Figure 1 is a side elevation of the improved beam compass.

Figure 2 is an enlarged fragmentary longitudinal section taken on the line 2—2 of Figure 1.

Figure 3 is an enlarged vertical section taken on the line 3—3 of Figure 1.

Figure 4 is an enlarged transverse section taken on the line 4—4 of Figure 1.

Figure 5 is a detail horizontal section taken on the line 5—5 of Figure 1.

Figure 6 is an enlarged vertical trans-

verse section through the improved beam compass showing the means for adjustably holding the marking leg or post in position on the beam.

60

Figure 7 is an enlarged fragmentary vertical longitudinal section through the same taken on the line 7—7 of Figure 4.

Figure 8 is a detail elevation of the marking pen adapted to be detachably associated with the movable post.

Figure 9 is a detail elevation of the means for forcing the lead from the lead carrying leg.

Figure 10 is an enlarged detail elevation 70 of the leg for carrying the marking lead.

Referring to the drawings, in detail, wherein similar reference characters indicate corresponding parts throughout the several views, the letter A generally indicates the improved beam compass which includes the main needle carrying post 15, the beam 16, the adjustable marking post 17, and the lead extractor 65.

75

The main or needle post 15 includes a central cylindrical body portion 18 which is provided on its opposite sides with flat faces 19 and with a bore 20 to conform with the reduced end 21 of the beam 16. The reduced end 21 of the beam is provided with 85 a flat face 22 which prevents the beam 16 from rotating in bore 20. The reduced end 21 of beam 16 is provided with a threaded bore 23 in which is fitted a clamping thumb screw 24. The clamping thumb screw is 90 adapted to engage the outer surface of the main or needle post 15 and to engage in the threaded bore 23 of beam 16 thereby drawing beam 16 against inner surface of needle post 15 and holding the beam in position thereon against accidental movement. Thus it can be seen when it is desired to substitute beam 16 for a similar beam of different length, it is merely necessary to remove the clamping screw 24 from bore 100 23 thereby permitting beam 16 to be detached from needle post 15.

95

The upper end of the post 15 above the cylindrical body portion 18 is knurled or serrated as at 25, and the end is concave as 105 at 26, so as to permit a firm grip to be had thereon by the draftsman. The lower end of the main or needle carrying post 15 is gradually tapered toward its free end, and is provided with a slotted recessed terminal for the reception of the needle 27 which is held in adjusted position against

105

110

accidental displacement by a tapered nut 28 which is threaded, in position on the threaded tapered lower portion of post 15.

The beam 16 includes a substantially cylindrical body with a reduced end 21, and the lower face of the body is flattened as at 29 and provided with a plurality of equi-distantly spaced transversely extending notches 30 and the forward face of the beam is graduated as at 31 and provided with suitable indicating numbers to conform to the graduations and the recesses 30 so as to permit of the convenient adjustment of the post 17. The extreme outer end of the beam 16 is provided with a head 32 which limits the outward movement of the adjusting marking post housing 33 thereon.

The adjustable marking post 17 is carried by the housing 33 which is slidably mounted on the beam 16, and this housing includes spaced end plates 34 and an intermediate partition plate 35. The end plates 34 above the partition plate 35 are provided on the inner faces with lugs 36, and with openings 37 for the beam 16, and these openings are shaped to conform to the cross sectional configuration of the beam. By this means the marking leg is held perpendicular, and parallel with needle post 15.

The end plates 34 of the partition plate 35 are provided with aligned openings 38 for the reception of the adjusting screw 39 which is mounted in the threaded bore 40 of the adjusting marking post 17. The outer end of the screw 39 is provided with a knurled head 41 by means of which the adjusting screw may be readily turned. The outer face of the partition plate 35 is provided with suitable graduations 42 and the marking post 17 carries an indicating point 43 which is adapted to co-operate therewith. This arrangement permits a fine adjustment of the marking post 17 to be had.

A substantially U-shaped thumb piece 44 is slidably mounted between the end plates 34 and the legs of the U-shaped member engage on opposite sides of the lugs 36, and the legs of member 44 have secured thereto a shoe 45 which is provided with an upwardly extending transversely arranged tooth 46, which is adapted to engage in any one of the recesses 30. One of the legs of the U-shaped thumb pieces 44 is provided with a sight opening, 67, the purpose of which will hereinafter more fully appear.

The outer face of the thumb piece 44 is roughed or serrated as at 47 so as to prevent the slipping of the operator's thumb thereon. The shoe 45 is normally held in engagement with the straight face 29 of the beam 16 by means of a leaf spring 48 which is carried by the housing 33 and the upper surface of the partition plate 35 is provided with a recessed portion 49 for the reception of spring 48. Thus it can be seen that lugs 36

act as guides for thumb piece 44, and prevent the dissolution of the marking leg as a whole, when it is desired to substitute a beam of different length for beam 16.

The lower end of the adjusting marking post 17 is provided with a vertically disposed bore 50 for the reception of the legs of the reduced portion 51 of the pencil marking leg 52 and the reduced portion 53 of the pen 54. The reduced portions 51 and 53 of the lead carrying leg 52 and the pen 54 are slotted as at 55 which permits of the contraction of the reduced portion when the same is fitted in the vertical bore 50 of the adjusting marking post 17. A pin 56 is carried by the adjusting or marking post 17 and the same extends through the bore 50 thereof and is adapted to fit in a transversely extended groove 57 formed in the reduced portions 51 and 53 of the lead carrying leg 52 and the pen 54. The upper ends of the reduced portions 51 and 53 of the lead carrying leg 52 and pen 54 are inclined as at 58 above the groove 57 so as to permit the flexing of the slotted reduced portions 51 and 53 of the pencil carrying leg 52 and the pen 54 when either one of the same is being placed in the bore 50 of the post 17. The leg 52 is provided with an inwardly extending smooth bore 59 for the reception of the marking lead 60 and this portion of the leg is slotted longitudinally as at 61 and the lower outer surface of the same is tapered as at 62 and is provided with external threads 63. An internally tapered nut 64 is mounted on the leg 52 and is adapted to bring the slit portions of the leg together to hold the marking lead 60 against accidental displacement.

The bore 59 of the leg 52 has slidably mounted therein a follower 65 of cylindrical formation, which is adapted to push the lead 60 out of the bore when the same has become worn down and the cylindrical follower 65 is provided with an outwardly extending handle or pin 66 which protrudes through the slot 61 formed in the leg. Thus it can be seen that when it is desired to remove the lead 60 from the bore it is merely necessary to loosen the nut 64 so to permit the leg to expand and the follower is then brought down the bore into engagement with the lead and thus effectively force the same out of the bore.

When it is desired to substitute the pen 54 for the leg 52 it is merely necessary to give the leg a sharp pull which will disengage the pin 56 from the groove 57 which will permit of the leg 52 being disengaged from post 17.

After the leg 52 has been removed from the post 17, the reduced portion 53 of the pen 54 is inserted into the bore 50 and when the tapered end thereof engages the pin 56 the same is forced inwardly until the pin 130

56 rides into the groove 57 formed in its outer surface.

In operation of the improved compass the leg 52 or the pen 54 is associated with the 5 post 17 according to the character of the work being executed, and the thumb piece 44 is moved downwardly against the tension of the spring 48 which moves the tooth 46 from out of engagement with the notches 30. 10 The housing is then moved to the desired place on the beam and the marking thereon can be readily seen through the opening 67 provided in the thumb piece 44 for that purpose. When it is desired to adjust the leg 15 52 a fraction of an inch, it is merely necessary to turn the adjusting screw 39 which will permit of as fine adjustment as desired. The compass is then used in the ordinary manner.

20 Various changes in form, proportions, size and details of the device may be had without departing from the spirit or sacrificing any of the advantages of my invention, but,

I claim:

25 1. A compass comprising a needle post, an outwardly extending beam carried by the post having a plurality of equi-distantly spaced notches formed on its lower face, a housing slidably mounted on said beam, a thumb piece slidably carried by the housing, a tooth carried by the thumb piece and arranged to engage in any one of said notches, spring means normally holding said thumb piece in a raised position and in engagement 30 with one of the notches, and a marking post adjustably carried by the housing.

35 2. A compass comprising a needle post, an outwardly extending beam carried by the needle post having a plurality of equi-distantly spaced notches formed therein, a housing slidably mounted on the beam, a shoe slidably carried by the housing, a tooth formed on the shoe and arranged to engage in any one of the notches, spring 40 means normally holding the shoe in engagement with the beam, a thumb piece carried by the plate for said shoe, a worm rotatably carried by the housing, a post slidably carried by the housing and having a threaded bore arranged to receive said worm, as and 45 for the purpose specified.

50 3. In a drawing instrument, a supporting post having a vertical bore and a pin carried by the post and arranged in said bore, of a leg having a reduced slotted terminal arranged to fit in said bore, the reduced terminal having a groove arranged to receive

said pin, and provided with an inclined surface arranged above said groove.

4. A compass comprising a needle post 60 having a diametrically extending opening formed therein, the wall of said opening having a flattened portion, a longitudinally extending graduated beam, a reduced extension formed on one terminal of the beam arranged to fit in the opening formed in the post, said reduced extension having a flattened face for engagement with the flattened portion of the wall of the opening, whereby rotary movement of the beam in 65 relation to the post is prevented, the body portion of the beam having a lower flattened face, a housing including end walls and a partition plate, inwardly extending lugs formed on the end walls and spaced 70 from the upper and side edges thereof, said side walls and lugs having aligned openings for receiving the beam, the walls of said openings having the lower portions thereof flattened for engagement with the 75 flattened face of the beam, whereby the housing is held in parallel relation with the post and against rotation on said beam, the flattened face of said beam having grooves 80 formed therein, a sliding shoe arranged between the end walls of the housing, a tooth formed on said shoe arranged to engage in any one of said grooves, a U-shaped thumb grip slidably mounted on said lugs and secured to said shoe, said thumb grip having 85 a sight opening therein to permit of the reading of the graduations on the beam, and an adjustable marking leg carried by the housing.

5. In a compass, the combination, with a 90 needle post, and a beam, of a marking post adjustably carried by said beam, and including resilient means for rigidly maintaining said marking post in position upon the beam.

95 6. In a compass, the combination, of a needle post; a beam, and a marker post, including a housing slidably carried upon said beam, said housing having guide lugs thereon, a substantially U-shaped thumb piece 100 reciprocably mounted upon said housing, a shoe member detachably connected to the open end of said U-shaped member, a spring detachably carried by said housing, and normally under compression to push said shoe 105 into engagement with said beam, and a marking point adjustably carried by said housing.

CHARLES C. REITENBAUGH.
